(57) **CLAIM**

The ornamental design for a skin moisture and oil analyzer, as shown and described.

DESCRIPTION

FIG. 1 is a perspective view of a skin moisture and oil analyzer in accordance with the present invention;

FIG. 2 is an elevational front view of the skin moisture and oil analyzer of FIG. 1;

FIG. 3 is an elevational rear view of the skin moisture and oil analyzer of FIG. 1;

FIG. 4 is an elevational left side view of the skin moisture and oil analyzer of FIG. 1;

FIG. 5 is an elevational right side view of the skin moisture and oil analyzer of FIG. 1;

FIG. 6 is a top plan view of the skin moisture and oil analyzer of FIG. 1; and,

FIG. 7 is a bottom plan view of the skin moisture and oil analyzer of FIG. 1.

The broken lines in the drawings depict portions of the skin moisture and oil analyzer that form no part of the claimed design.

1 Claim, 5 Drawing Sheets
